Primary Examiner — Clare E Heflin(74) *Attorney, Agent, or Firm* — Lewis Roca Rothgerber Christie LLP(57) **CLAIM**

The ornamental design for the lamp, as shown and described.

DESCRIPTION

FIG. 1 is a front and lower left perspective view of a lamp according to the present invention;

FIG. 2 is a front and upper right perspective view of the lamp of FIG. 1;

FIG. 3 is a front elevational view of the lamp of FIG. 1, the rear view being a mirror image;

FIG. 4 is a side elevational view of the lamp of FIG. 1, the right and left views being mirror images of one another;

FIG. 5 is a top plan view of the lamp of FIG. 1; and,

FIG. 6 is a bottom plan view of the lamp of FIG. 1. The broken lines shown on the drawings depict portions of the lamp that form no part of the claimed design.
